CLAIM

The ornamental design for a lavatory fixture with integrated faucet, soap dispenser, and hand dryer, substantially, as shown and described.

DESCRIPTION

FIG. 1 is a raised perspective view of a lavatory fixture with a faucet, soap dispenser, and hand dryer all-in-one;

FIG. 2 is a front perspective view of the lavatory fixture, as shown in FIG. 1;

FIG. 3 is a front view of the of the lavatory fixture, as shown in FIG. 1;

FIG. 4 is a rear view of the lavatory fixture, as shown in FIG. 1;

FIG. 5 is a right side view of the lavatory fixture, as shown in FIG. 1;

FIG. 6 is a left side view of the lavatory fixture, as shown in FIG. 1;

FIG. 7 is a top view of the lavatory fixture, as shown in FIG. 1; and,

FIG. 8 is a bottom view of the lavatory fixture, as shown in FIG. 1.

The broken lines shown in the drawing represent a portion of the lavatory fixture that forms no part of the claimed design.

The appearance of any portion of the article between the jagged broken away symbols shown in the drawings forms no part of the claimed design.
